UNITED STATES PATENT OFFICE.

FRANK PERRY, OF FRESNO, CALIFORNIA.

CARBURETER.

1,142,763.

Specification of Letters Patent.

Patented June 8, 1915.

Application filed August 31, 1914. Serial No. 859,415.

To all whom it may concern:

Be it known that I, FRANK PERRY, a citizen of the United States, and a resident of the city of Fresno, county of Fresno, and 5 State of California, have invented a new and useful Improvement in Carbureters for Internal-Combustion Engines, of which the following is a specification.

My invention relates to a new and improved means for atomizing the liquid fuel used in internal combustion engines and mixing it with the air, whereby a more combustible mixture is obtained than that produced by the carbureters heretofore in use. 10 In the drawings which accompany this specification, and which is hereby made a part hereof, Figure 1 is a side sectional view of the carbureter complete. Fig. 2 is a perspective view of the shutter showing the 15 atomizer in the relative position it is placed when the carbureter is assembled. Fig. 3 is an end view of the cap which covers the ends of the throttle chamber. Fig. 4 shows one form of the outer tube of the atomizer. Fig. 5 shows another form of the outer tube 20 of the atomizer. Fig. 6 is the inner tube of the atomizer.

In said drawings A is a float chamber which is adapted to contain liquid fuel.

30 13 is the fuel intake, and 2 the float.

17 is a valve which cuts off the inflow of gasolene when the liquid fuel in the chamber rises to a predetermined height in the float chamber.

35 B is the throttle chamber which is tubular in form and has an air intake 10.

D is the mixing chamber attached to the throttle chamber B with an opening 12 between them.

40 7 is an end cap which is constructed to fit snugly over the ends of throttle chamber B, having a bearing 18 in the center thereof to permit axle 9 to pass through.

C is the shutter which is constructed in 45 the form of a lateral section of a tube having one of the edges thereof cut diagonally, which said shutter fits turnably within the throttle chamber, and having a member 19 in the form of a segment of a circle at each 50 end thereof. To the center of member 19 there is an axle 9, heretofore referred to, attached.

55 14 is a lever attached to axle 9, the purpose of which is to rotate within limits, the shutter within the throttle chamber. The axle 9 rests in bearings 18.

E is the atomizer which consists of an inner tube 4, constructed with a lateral slot 20 therein which when the carbureter is assembled is on the upper side and opens into the mixing chamber D. Inner tube 4 is held in a rigid position, and when assembled is closed at both ends, and has a lead 3 constructed to transmit liquid fuel from the float chamber to the inside of such inner tube 4.

5 is an outer tube which fits snugly and rotatably over inner tube 4, having a lever 15 at one end thereof adapted to rotate outer tube 5 on said inner tube 4. Outer tube 5 is 70 open at both ends and has lateral rows of holes 17, 22 and 23 therein. All of the holes in any one row are of approximately the same size, but each row of holes is of a different size. In my construction I prefer 75 to have such rows of holes decrease in succession. In assembling the carbureter the relation of inner tube 4 and outer tube 5 should be such that by moving lever 15 either one of such rows of holes 17, 22, or 23, 80 will register with lateral slot 20. Fig. 5 shows a modified form of outer tube 5, the difference between the two being that instead of a plurality of rows of holes 17, 22 and 23, there is substituted triangular 85 incisions 16.

The atomizer E is assembled in the carbureter in the opening 12, directly under the shutter C, so that when shutter C is open the holes in the outer tube and the slot in 90 the inner tube open toward the mixing chamber. When throttle C is partly closed a part of such rows of holes is covered, as the shutter is placed within the throttle chamber so the oblique edge is adjacent to 95 the opening 12. The object of this construction is to decrease the flow of liquid fuel when the supply of air is decreased by one movement of the shutter C. As the holes in the outer tube 5 and the slot 20 in 100 inner tube 4 are very small, the fuel is drawn through it only by suction, and when the shutter C simply covers the holes the suction is prevented and the fuel will not flow except from those holes which are registered 105 with the slot 20 and which are uncovered.

I claim as my invention and desire Letters Patent upon:

1. In a carbureter, the combination of a float chamber constructed to hold liquid fuel, an inlet to such float chamber, a mixing chamber having an outlet opening, a

throttle chamber having an opening into such mixing chamber, a shutter within such throttle chamber constructed to regulate the size of the opening between the throttle chamber and the mixing chamber by hand means, and an atomizer consisting of an inner tube having a lateral slot therein and closed at each end, and rigidly attached to the walls of the throttle chamber adjacent to the opening between the throttle chamber and the mixing chamber, with the slot therein opening toward such mixing chamber, a lead from the float chamber to such inner tube constructed to carry liquid fuel from such float chamber to such inner tube, and an outer tube constructed to fit over such inner tube, and having a plurality of holes therein, hand means for turning such outer tube to bring a series of holes to register with the slot in the inner tube, said atomizer being placed in such relation to the shutter that in partially closing the opening between the throttle chamber and the mixing chamber a portion of such holes is covered with the shutter, and an opening into such throttle chamber to admit air therein, all substantially as described.

2. In a carbureter, the combination of a float chamber, an inlet to such float chamber, a throttle chamber, an inlet to such throttle chamber constructed to admit air into such throttle chamber, a mixing chamber, an opening between such throttle chamber and mixing chamber, a shutter within such throttle chamber constructed to regulate the size of the opening between the throttle chamber and the mixing chamber, hand means for regulating such shutter, an atomizer consisting of an inner tube having the ends thereof closed and a slot therein located within such throttle chamber within the opening between the throttle chamber and the mixing chamber and just under the path of such shutter, and with the slot opening toward such mixing chamber, an outer tube constructed to fit over such inner tube and to be rotated by hand means, having a series of triangular holes in a lateral row through the wall of such outer tube, and adapted to register a portion of such triangular holes with the slot in such inner tube, a lead from such float chamber to such inner tube, and an outlet from such mixing chamber, all substantially as described.

3. In a carbureter, the combination of a float chamber, an inlet to such float chamber, a throttle chamber constructed tubular in form and having the ends thereof closed, an

air inlet to such throttle chamber, a mixing chamber, an opening between such throttle chamber and mixing chamber, a shutter within such throttle chamber consisting of a lateral section of a tube adapted to fit snugly within such throttle chamber, having one edge thereof cut obliquely to the end of such shutter, and having a member to sustain an axle, and an axle attached thereto, bearings in the end walls of such throttle chamber constructed to carry such axle and permit the shutter to turn within such throttle chamber, hand means for turning such shutter, an atomizer having openings toward such mixing chamber and located within the path of such shutter and directly under it so in shutting off the opening between the throttle chamber and the mixing chamber a portion of such openings in such atomizer are closed, a lead from such float chamber to such atomizer, all substantially as described.

4. In a carbureter, the combination of a float chamber, an inlet to such float chamber, a mixing chamber having an outlet opening, a throttle chamber tubular in form and having an opening therein for taking air, and a connection opening into such mixing chamber, a rotary shutter within such throttle chamber constructed to regulate the size of the opening between the throttle chamber and the mixing chamber, an atomizer within such throttle chamber just under the path of such rotary shutter and within line of the opening between the throttle chamber and the mixing chamber, such atomizer consisting of an inner tube closed at both ends and having a lateral slot therein opening toward such opening between the throttle chamber and the mixing chamber, and an outer tube constructed to fit over such inner tube, and having a plurality of lateral rows of holes through the wall of such outer tube, all of the holes in each row being approximately uniform in size, and the size of the holes of each row being of a different size, decreasing with each successive row, such rows of holes being far enough apart so but one row can register with the slot in such inner tube at one time, and means for rotating such outer tube to bring either of such rows of holes to register with the slot in such inner tube, all substantially as described.

FRANK PERRY.
